[57] CLAIM

The ornamental design for a display processing system, as shown and described.

DESCRIPTION

FIG. 1 is a perspective view of a display processing system showing our new design;

FIG. 2 is a front elevational view thereof on a slightly reduced scale;

FIG. 3 is a right side elevational view thereof on a slightly reduced scale;

FIG. 4 is a left side elevational view thereof on a slightly reduced scale;

FIG. 5 is a top plan view thereof on a slightly reduced scale;

FIG. 6 is a rear elevational view thereof on a slightly reduced scale;

FIG. 7 is a rear elevational view of the keyboard on a reduced scale, the terminal being omitted for purposes of disclosure.
